LAPPING METHOD AND APPARATUS

Harold E. Snyder, Massillon, Ohio, assignor to
Clarence I. McAllister, Massillon, Ohio

Application December 8, 1933, Serial No. 701,483

4 Claims. (Cl. 51—26)

My invention relates to methods and apparatus for simultaneously lapping preferably spherical seat surfaces on three parts or members, including a central part or member having opposite convex spherical surfaces thereon and two end parts or members each having a concave spherical surface therein for fitting one of the convex surfaces of the central part or member.

Such parts or members may be used for example in connection with a packless union for a water pump such as set forth in U. S. Letters Patent No. 1,792,786, for Sealing means, issued February 17, 1931 to Harry J. Walker.

The three parts or members for such a packless union may include a central hardened steel seal disk ring having coaxial opposite spherical and annular convex faces thereon, and two hardened steel end rings each having a spherical and annular concave seat face thereon for fitting one of the convex seat faces on the seal disk ring.

It is essential that each set of interfitting spherical faces be finished to substantially Johannsen gauge accuracy with respect to each other, and for this purpose it has been heretofore necessary to hand lap the interfitting seat faces of the three parts.

Such hand lapping operations as heretofore carried out are relatively slow and costly.

The objects of the present invention include the provision of an improved method and apparatus whereby the interfitting seat surfaces of the three parts may be rapidly lapped, preferably by the use of power driven means, thereby reducing the cost of providing the necessary accurately interfitting seat faces, and at the same time enabling mass production of the parts, and a consequent greater use of the packless water pumps in automobiles and the like.

The foregoing and other objects are attained by the methods, apparatus, parts, combinations, and sub-combinations, which comprise the present invention, and the nature of which is set forth in the following general statement, and preferred embodiments of the apparatus together with the preferred mode of use in carrying out the improved methods, are set forth in the following description, and which are particularly and distinctly pointed out and set forth in the appended claims forming part hereof.

The nature of the improved lapping method of the present invention may be described in general terms as including abutting two end members each having a concave spherical seat formed therein against opposite sides of a central disk member having opposite convex spherical seats

therein, each concave spherical seat interfitting with one of the convex spherical seats, applying a lapping compound between the interfitting seats, and simultaneously rotating the end members in the same direction about axes which intersect at the center of the central member.

The nature of the improved apparatus of the present invention may be described in general terms as including two power driven spindles whose longitudinal axes are angled to and intersect each other, means rotating the spindles in the same direction, opposite ends of the spindles being spaced from each other, each of the opposed ends of the spindles being provided with chuck means for releasably mounting one of the end members of the union for rotation about the spindle axis, means yieldingly urging one of the spindles towards the other, and means for starting and stopping rotation of the spindles and simultaneously feeding lapping compound to the union members when the spindles start to rotate.

One embodiment of the improved apparatus hereof adapted for carrying out the improved method hereof, is illustrated in the accompanying drawings forming part hereof, in which

Figure 1 is a longitudinal sectional view of a flanged end sleeve mounting one end ring of the union, the lap finishing of the parts of which the improved method and apparatus is particularly adapted;

Fig. 2, a side elevation view of the central seal ring of the union;

Fig. 3, a transverse sectional view of the other end ring of the union;

Fig. 4, a top plan view with portions broken away and illustrated in section of the improved apparatus with the three union parts to be lapped in place ready for operation of the apparatus for lapping the spherical seat surfaces on the three union parts;

Fig. 5, a fragmentary enlarged sectional view of the spindle portions of Fig. 4 more clearly illustrating details of construction and arrangement of the apparatus and the union parts;

Fig. 6, a front elevation view with portions broken away and illustrated in vertical section, illustrating certain parts of the apparatus in their relative positions during lapping operation of the same when the spindles are rotating;

Fig. 7, a fragmentary plan sectional view of one of the check valves of the improved lapping compound feeding means of the apparatus, as on line 7—7, Fig. 6; and

Fig. 8, a view similar to Fig. 6 illustrating certain parts of the apparatus in their relative

positions when the spindles are stopped permitting loading or removing of the union parts in or on the chucks of the spindles.

Similar numerals refer to similar parts throughout the several views.

The improved lapping apparatus is indicated generally by 10 and is adapted for carrying out the improved method hereof for lapping interfitting spherical seat faces on a three part union 10 indicated generally by 11.

The three part union as illustrated comprises parts of a packless union for a water pump such as set forth in U. S. Letters Patent No. 1,792,786, and includes a central hardened steel seal disk 15 ring 12 and two hardened steel end rings 13 and 13'.

The central seal disk ring 12 is formed with a central externally cylindric face 15 and opposite convex spherical and annular or zone seat faces 16 and 17, the faces 16 and 17 comprising opposite and similar zones of spherical surfaces having centers on the axis indicated by the dot-dash line 18, of the cylindric face 15.

The seal disk ring 12 has an internally cylindric bore 19 whose axis is also the axis 18 and the convex spherical zone faces 16 and 17 terminate at their outer ends in smaller circular corner intersections 20 and 21 respectively with the central cylindric bore 19, and the spherical zone faces 16 and 17 terminate in opposite inner ends in larger circular corner intersections 22 and 23 respectively with the cylindric face 15.

The planes of the circular corner intersections 22 and 23 are parallel with each other and are 35 equally spaced from the central plane 24 of the ring, normal to the axis 18.

The planes of the circular corner intersections 20 and 21 are parallel with each other and with the planes of the circular corner intersections 40 22 and 23 and are equally spaced therefrom.

Accordingly the convex spherical zone faces 16 and 17 may be otherwise stated as being oppositely and similarly disposed with respect to the center 25 of the seal disk ring 12, and the radii 45 of the spherical faces 16 and 17 as illustrated are preferably equal.

The end ring 13 is formed with a central internally cylindric bore 26, and an outer cylindric surface 27, each cylindric surface having the axis, indicated by the dot-dash line 28, and at one end the end ring 13 has a flat annular end face 29 normal to the axis 28 and at the other end a flat annular end face 30 likewise normal to the axis 28. A concave spherical and annular or zone face 31 is located between the internally cylindric bore 26 of the end ring 13 and the annular flat end face 30, and the spherical seat face 31 terminates at its outer end in a larger circular corner intersection 32 with the flat end face 30, the center of the spherical face 31 being on the axis 28 and the radius of the concave spherical face 31 of the end ring 13 being substantially equal to the radius of the convex spherical face 17 of the seal disk ring 12 so that the spherical faces 17 and 31 may interfit with each other.

The end ring 13 as illustrated is mounted in a counterbore provided in one end of a sleeve 33, the sleeve 33 being preferably provided with a flange 33' at its end mounting the end ring 13. The sleeve 33 has an internally cylindric bore 34 which is coaxial with the bore 26 of the end ring 13. The flanged sleeve 33 as illustrated is used in connection with a certain form of the packless union.

75 The end ring 13 as illustrated is substantially

identical with the end ring 13, the end ring 13' being formed with a central internally cylindric bore 26', and an outer cylindric surface 27', each cylindric surface having the axis, indicated by the dot-dash line 28', and at one end the end ring 13' has a flat annular end face 29' normal to the axis 28' and at the other end a flat annular end face 30' likewise normal to the axis 28'. A concave spherical and annular or zone face 31' is located between the internally cylindric bore 26' of the end ring 13' and the annular flat end face 30', and the spherical seat face 31' terminates at its outer end in a larger circular corner intersection 32' with the flat end face 30', the center of the spherical face 31' being on the axis 28' and the radius of the concave spherical face 31' of the end ring 13' being substantially equal to the radius of the convex spherical face 16 of the seal disk ring 12 so that the spherical faces 16 and 31' may interfit with each other.

For the successful operation of the particular union 11, it is essential that the interfitting spherical faces 16 and 31', and 17 and 31, be finished to substantially Johannsen gauge accuracy.

Prior to the present invention, the finishing of the interfitting seat faces has been by hand lapping operations which have been relatively slow, costly, and permitting only a limited production.

The apparatus 10 is particularly adapted for rapidly lap finishing the interfitting seat faces of each set of three union parts including a seal disk ring 12 and end rings 13 and 13'.

The improved lapping apparatus 10 includes a 35 table frame indicated generally by 41 and having a top 42 on which improveded spindle means 43 and 44 are operatively mounted.

The spindle means 43 includes a bearing block 45 in which a spindle 46 is mounted for rotation, preferably by anti-friction bearing means 47 and 47'.

The spindle 46 includes a spindle sleeve 48 having opposite ends extending beyond opposite ends of the bearing block 45. On the outer end 45 of the spindle sleeve 48 a drive pulley 49 is secured.

Retracting chuck means indicated generally by 50 are operatively mounted in and on the spindle sleeve 48, the engaging means 51 of the 50 chuck means 50 being located at the inner end of a rod 50-1 slidably mounted in the spindle sleeve 48.

The spindle means 44 includes a bearing block 52 in which the spindle 53 is mounted for rotation, preferably by anti-friction bearing means 54 and 54'.

The spindle 53 includes a spindle sleeve 55 having opposite ends extending beyond opposite ends of the bearing block 52. On the outer end 60 of the spindle sleeve 55 a drive pulley 56 is secured.

Chuck or collet means indicated generally by 57 are operatively mounted on the spindle sleeve 55, the engaging means 58 of the chuck means 57 being located at the inner end of the spindle 53 opposite the engaging means 51 of the chuck means 50 of the spindle 46.

The axis of rotation of the spindle 46 is indicated by the dot-dash line 59 and the axis of rotation of the spindle 53 is indicated by the dot-dash line 60.

The axes 59 and 60 are angled with respect to each other and intersect at the point 61 between the bearing blocks 45 and 52.

The improved lapping apparatus 10 furthermore includes means for driving both spindles 46 and 53 in the same direction of rotation, and as illustrated the driving means is indicated generally by 62 and includes a drive sleeve 63 mounted for rotation on the table frame 41 below the table top 42, as by anti-friction bearing means 64.

On one outer end of the drive sleeve 63 a drive pulley 65 is provided and the drive pulley 65 is drive connected as by means of a belt 66 with a drive motor, not shown.

On the other outer end of the drive sleeve 63 a female clutch member 67 is provided.

15 A countershaft 68 extends through the bore of the drive sleeve 63 and has one end rotatably mounted in the frame 41 as by anti-friction bearing means 69, and the other end rotatably mounted in the drive sleeve 63 as by anti-friction bearing means 70.

20 A male clutch member 71 is slidably keyed on the countershaft 68 adjacent the female clutch member 67 and the countershaft 68 has a shoulder 72 formed thereon, and a compression spring 73 is interposed between the shoulder 72 and the male clutch member 71 normally urging the male clutch member 71 into engagement with the female clutch member 67, and when the clutch members are engaged, the countershaft 68 is rotated by and with the drive sleeve 63.

25 The male clutch member 71 is formed with an outwardly opening annular groove 74 which preferably has at the sides thereof friction rings 75 and 75'.

30 A yoke 76 has its lower forked end 77 extending into the groove 74 between the friction rings 75 and 75', and the upper end 78 of the yoke 76 is secured to a collar 79, and the collar 79 is preferably adjustably mounted on a slide shaft 80 slidably mounted in the frame 41.

35 The countershaft 68 has a driving pulley 81 secured on one end thereof in driving alignment with the pulley 49 of the spindle means 43, and a belt 82 provides a driving connection between the driving pulley 81 and the pulley 49 of the spindle means 43.

40 The countershaft 68 also has a driving pulley 83 secured thereon at its other end in driving alignment with the driven pulley 56 of the spindle means 44, and a belt 84 provides a driving connection between the countershaft driving pulley 83 and the driven pulley 56 of the spindle means 44.

45 Accordingly, the spindles 46 and 53 are driven in the same direction when the countershaft 68 is in driving engagement with the drive sleeve 63, as shown in Fig. 6.

50 A compression spring 87 is interposed between the collar 79 and one of the frame members 88 and normally urges the slide shaft 80 in the direction of the arrow 89.

55 Cam tongues 90 are secured on the outer side of the frame member 88 and coact with cam notches 91 and cam tongues 91' provided on the adjacent end of a cam sleeve 92 which is rotatably mounted on the outer end of the slide shaft 80, and which is provided with a handle 93.

60 Accordingly the spring 87 yieldingly abuts the cam sleeve 92 with the cam notches 91 against the cam tongues 90 when the handle 93 is located in the position shown in Fig. 6.

65 When the handle 93 is turned to the position shown in Fig. 8, the cam tongues 91' of the cam sleeve 92 ride over the frame cam tongues 90

and slide the shaft 80 in the direction of the arrow 94, and accordingly disengages the male clutch member 71 slidably keyed on the countershaft, from the female clutch member 67 carried on the drive sleeve 63, as aforesaid, with the yoke forked end 77 abutting against the friction ring 75 in the groove 74, and not only serving to retract the male clutch member 71 from the female clutch member 67, but also serving to brake the same, and thus stop rotation of the countershaft 68.

70 Means indicated generally by 95 and actuated by movement of the slide shaft 80 are provided for automatically delivering a measured quantity of lapping compound, such as an emery dust 15 and an oil mixture, to a point 96 which is within the bore of a seal ring 12 being lapped in a machine, from which the delivered charge of lapping compound centrifuges out between the abutting spherical zone faces of the three union 20 parts 12, 13, and 13' being lapped.

75 The lapping compound feeding means 95 includes a base member 97 which is mounted on a plate 98 carried on the outer end of arms 99 the inner ends of which are secured to the table 25 top 42.

80 A lower compartment 100 is formed by a counterbore 100' provided in the lower face of the base member 97 and by the upper face of the plate 98.

85 A duct 101 communicates between the compartment 100 and one end of a feed tube 102 which is screwed into the base member 97, and which extends through the bore of the spindle sleeve 55, and the other end of the feed tube 102 35 terminates at the point 96.

90 The base member 97 has an upper compartment 103 formed by an upper counterbore 103' therein, and by a diaphragm 104 extending across the upper end of the upper counterbore 40 103'.

95 A port 105 communicates between the lower compartment 100 and the upper compartment 103 and a spring pressed check valve 106 is cooperatively associated with the port 105.

100 The diaphragm 104 is centrally connected with a check valve casing 107 which includes inlet openings 108, an outlet opening 109 and a spring pressed check valve 110 interposed therebetween.

105 Above the diaphragm 104 a tubular member 111 has its lower threaded end screwed into the threaded upper end of the counterbore 103' and a screen closure 112 may be provided for the upper end of the bore of the tubular member 111.

110 A diaphragm rod 113 is secured at its lower end 55 to the upper end of the valve casing 107 and the rod 113 passes through an opening formed in the screen closure 112 and through a guide opening formed in a guide bracket 114 secured to the upper end of the tubular member 111.

115 Above the guide bracket 114 the upper end of the rod 113 is connected to one end of a supporting bar 115, the other end of which is connected preferably adjustably as by nuts 116 with the threaded upper end of a push rod 117. The push rod 117 is slidably mounted in a vertical guide tube 118 the lower threaded end of which is screwed in a threaded bore formed in the plate 98.

120 The limit of downward travel of the push rod 117 and thus of the diaphragm rod 113 is adjustably determined as by means of a nut 119 screwed on the threaded upper end of the push rod 117, and abutting against the upper end of 75

the guide tube 118 at the desired position of maximum downward travel as shown in Fig. 6.

The lower end of the push rod 117 extends below the lower end of the guide tube 118 below the plate 98, and a flanged nut 120 is screwed on a threaded portion of the lower end of the push rod 117 and a compression spring 121 is interposed between the flanged nut 120 and a lock nut 122 screwed on the threaded lower end of 10 the guide tube 118, thereby normally urging the push rod 117 downwardly.

A rocker arm 123 is pivotally mounted intermediate its ends as by a pivot bolt 124 secured in the lower ends of members 125 depending 15 from the arms 99.

The outer end of the rocker arm 123 has an adjustable push rod actuating head 126 screwed therein, and the inner end of the rocker arm 123 is pivotally secured to one end of a link 127, the 20 other end of which is pivotally secured to the adjacent end of the slide shaft 80.

In Fig. 8 the relative positions of the parts of the apparatus 10 are shown when the spindles have been stopped, union parts having been 25 loaded on the spindle chucks and when the slide shaft 80 is in its position of extreme displacement in the direction of the arrow 94, and the rocker arm head 126 is elevated so as to elevate the push rod 117 and the diaphragm rod 113 and 30 the diaphragm 104.

The tubular member 111 is filled with lapping compound and when the diaphragm rod 113 and diaphragm 104 are elevated to the positions shown in Fig. 8, the check valve 110 opens and the check 35 valve 106 closes, thereby permitting a charge of lapping compound to pass from the bore of the tubular member 111 through the check valve 110 into the upper compartment 103.

When the handle 93 is turned to the position 40 shown in Fig. 6, the slide shaft 80 is moved to its position of extreme displacement in the direction of the arrow 89, and the outer end of the rocker arm 123 drops permitting the spring 121 to move the push rod 117 and the diaphragm rod 45 113 downwardly, thus bringing the diaphragm 104 to the position shown in Fig. 6, in which the upper check valve 110 is closed and the lower check valve 106 is opened and a charge of lapping compound has been fed through the bore of the 50 tube 102 to the point 96 within the bore of the seal disk ring 12 of the three union parts loaded in the apparatus ready for lapping.

Simultaneously, the male clutch member 71 has been permitted to engage with the female clutch 55 member 67 and the union parts 12, 13 and 13' are lapped, by operation of the apparatus rotating the end rings of the union parts about their axes 28 and 28' intersecting each other at the center 25 of the seal disk ring 12, the end rings 13 and 60 13' rotating in the same direction.

After the parts have been lapped sufficiently, the chuck 51 is retracted and the union parts are removed from the chucks of the apparatus, and another set of three union parts is inserted into 65 the chucks of the machine.

In the illustrated form of the apparatus 10, the retracting chuck means 50 is provided in its engaging means 51 with a rubber washer 51' which yieldingly backs each end ring 13' carried in the 70 engaging means 51.

The engaging means 58 of the chuck or collet means 51 as illustrated is arranged to carry successively flange sleeves 33 in which the end rings 13 are mounted as heretofore described.

75 As aforesaid, the engaging means 51 is mounted

on the inner end of a rod 50-1 slidably mounted in the spindle sleeve 48.

The other end of the rod 50-1 extends beyond the pulley 49, and a counterbored sleeve 50-2 is slot and pin connected at one end 50-3 with the outer end of the rod 50-1 and is provided at its other end 50-4 with a releasable bayonet joint connection with the spindle sleeve 48, and within the counterbore of the sleeve 50-2 a collar 50-5 is secured on the rod 50-1, and a compression spring 50-6 is interposed between the collar 50-5 and the bottom of the counterbore of the sleeve 50-2.

Accordingly when the sleeve 50-2 has its bayonet joint connection engaged with the spindle 15 sleeve 48, the spring 50-6 yieldingly urges the rod 50-1 and the chuck engaging means 51, towards the opposite chuck engaging means 58, thereby abutting union parts 13 and 13' mounted respectively in the engaging means 58 and 51 20 against a mating seal disk ring 12 located therebetween.

When the sleeve 50-2 is operated to release its bayonet joint connection with the sleeve 48, the rod 50-1 may be retracted or withdrawn, to the 25 position shown in Fig. 8, thereby permitting unloading and loading of the chuck engaging means.

It is to be particularly noted, that in the lapping method as carried out by the improved apparatus above set forth, rotation of the union 30 end members in the same direction, with the central disk ring member therebetween and with the concave annular spherical zone seats of the end members fitting against the convex seats of the central disk ring member, serves to simultaneously 35 lap the spherical seat surfaces of all the members because the rotation of the end members in the same direction gives rise to a continuous slippage or creep of the central member with respect to both end members, thereby 40 attaining the desired lapping action.

When the end members are rotated in opposite directions in abutment with a central disk member, the end members and the central disk member having the described interfitting spherical 45 zone seats, the central disk member sticks in the spherical zone seat of one of the end members and it is impossible to effect the desired lapping.

I claim:

1. The method of lap finishing spherical zone 50 seats on three members including a central disk member having opposite convex spherical zone seats thereon and two end members each having a concave spherical zone seat therein and 55 each concave seat interfitting with one of the convex seats, which includes abutting the members together so that each concave seat fits against one of the convex seats, and simultaneously rotating the end members in the same direction, the axes of rotation of the end members being angled with respect to each other.

2. The method of lap finishing spherical zone 60 seats on three members including a central ring disk member having opposite convex spherical zone seats thereon and two end members each having a concave spherical zone seat therein and 65 each concave seat interfitting with one of the convex seats, which includes abutting the members together so that each concave seat fits against one of the convex seats, and simultaneously rotating the end members in the same direction, and introducing lapping compound within the opening of the ring disk member and between the abutting seats of the rotating members.

3. The method of lap finishing spherical zone seats on three members including a central ring disk member having opposite convex spherical zone seats thereon and two end disk members each having a concave spherical zone seat therein and each concave seat interfitting with one of the convex seats, which includes abutting the members together so that each concave seat fits against one of the convex seats, and simultaneously rotating the end members in the same direction about intersecting angled axes, and introducing lapping compound within the opening of the ring disk member and between the abut-

ting seats of the rotating members from a point adjacent the intersection of the axes of rotation.

4. Apparatus for lapping and the like including two spindles each operatively mounted for rotation about a longitudinal axis, the spindles having opposite ends spaced from each other, chuck means on each opposite spindle end, means for rotating the spindles, and means for feeding successive charges of lapping compound between the opposite chuck means, and common means controlling the operation of the spindle rotating means and the lapping compound feeding means.

HAROLD E. SNYDER.
